(57) **CLAIM**

The ornamental design for a flexible light, as shown and described.

DESCRIPTION

FIG. 1 is a perspective view of my design;

FIG. 2 is a front view thereof;

FIG. 3 is a back view thereof;

FIG. 4 is a left side view thereof, the right side being a mirror image thereof; and,

FIG. 5 is a top view thereof.

The oblique lines on the lens of my flexible light indicate that the lens is at least translucent and may be transparent.

The dashed lines in the figures form no part of the claimed design. All other surface(s) or portion(s) of my flexible light not shown in the figures or otherwise described in the specification, such as the bottom thereof and such as the location behind the lens as well as the thickness of the lens, form no part of the claimed design.
